UNITED STATES PATENT OFFICE

GUSTAV EGLOFF AND HARRY P. BENNER, OF CHICAGO, ILLINOIS, ASSIGNORS TO UNIVERSAL OIL PRODUCTS COMPANY, OF CHICAGO, ILLINOIS, A CORPORATION OF SOUTH DAKOTA

PROCESS FOR CRACKING HYDROCARBON OILS

Application filed August 20, 1920. Serial No. 404,912.

This invention relates to a process for treating heavy petroleum oils, such as the residual products obtained in the distillation of petroleum, whereby such heavy oils are converted by means of heat and pressure into lighter oils such as gasoline, kerosene, gas oil or the like.

Among the salient objects of the invention are to provide a process in which relatively heavy or residual oils, as for example, fuel oil from petroleum, are cracked in a so-called continuous process, in such a way as to avoid clogging up or injuring the apparatus by carbon deposition, particularly in that part of the apparatus which is subjected to more or less direct heat action while at the same time obtaining a maximum yield of gasoline with minimum fuel consumption; to provide a process of the character referred to in which a maximum amount of charging stock is fed through the apparatus in a given unit of time and with relation to the area of heating surface in the fire zone while at the same time permitting a maximum predetermined production of gasoline or the like hydrocarbon desired to be produced; to provide a process of the character in question which will produce gasoline-like bodies from such residual oil at the rate of at least 20 percent per hour of the charging stock; to provide a process of the character referred to which treats in excess of one gallon of charging oil per square foot of heating surface in the fire zone per hour, or in other words, permits of feeding the residual oil through the fire zone at a rate of not less than 200 gallons of residual oil per hour for every 200 square feet of heating area, while at the same time producing gasoline at the rate aforementioned; to provide a process in which the residual oil is cracked to the extent of converting and removing from the vapor chamber in the form of vapor in excess of 50 percent of the oil charged per hour; to provide a process of the character aforesaid in which regulatable proportions of said vapors and more particularly the heavier parts thereof are condensed and collected separately from the lighter parts thereof, whereby said heavier parts are available for and amenable to further cracking and

which may be continuously returned to and mixed with the fresh charging stock passing through the fire zone; to provide a process in which the character of the reflux condensate referred to may be so regulated as to permit of returning to the system for further cracking reflux condensate which is free from light hydrocarbons, as for example, gasoline like bodies, and which in itself forms a charging stock capable of being converted into such gasoline like bodies; to provide a process of the character in question in which the residual oil is converted into gasoline like bodies and distillation products in which the latter in effect constitute a charging stock which is continuously being produced simultaneously with the gasoline like bodies referred to; to provide a process for cracking residual oil whereby there is provided pressure distillate which contains less unsaturated hydrocarbons than the original residual oil which formed the charging stock; to provide a process in which heavy residual oil, as for example, fuel oil or petroleum tar, may be converted into gasoline, kerosene and gas oil in varying percentages, as for example: 19 to 32 percent gasoline, 8 to 14 percent kerosene, 11 to 20 percent gas oil, to provide a process of cracking the residual oil or petroleum tar referred to, in which the oil is so treated in the heating or fire zone that only a negligible amount of carbon is precipitated in the heating tubes or more specifically, the carbon so precipitated may not be more than 0.03 lbs. per gallon of oil charged through the heating tubes; to provide a process in which the fuel oil or petroleum tar referred to may be converted into the light hydrocarbons hereinabove mentioned at a relatively low fuel cost; to provide a novel product produced by the process; to provide a pressure distillate produced by the cracking of petroleum tar, which pressure distillate has a lower percentage of unsaturated hydrocarbons than the petroleum tar from which it was produced, and in general to provide improvements of the character hereinafter set forth.

Before describing the apparatus in which we may carry out our invention, it may be noted that our process has heretofore been

carried out in commercial operation in the treatment of petroleum tars produced as a residue from the distillation at atmospheric pressure of crude petroleum oil from the 6 Wayside, Augusta-Elbing, fields of Kansas and the Delaware field of Oklahoma. It may also be noted that these residual oils were between 21.6 and 24.3 Baumé gravity. These 10 petroleum tars are also known and sold as fuel oils, and for fluxes for hard asphalts, and certain of the asphaltic constituents which are sometimes recovered by further distillation at atmospheric pressure, and by 15 oxidation. By the petroleum tar is also included such natural heavy oils as heavy Mexican and California crudes which are more or less devoid of the lighter hydrocarbons herein desired to be produced.

By no known prior process has it been possible to commercially crack the petroleum tars or residual oils above referred to; one 20 principal objection being that oils of this character produce such large amounts of carbon, it has not been commercially feasible to 25 crack them. By our process we avoid the precipitation or formation of carbon in that portion of the apparatus in which the charging oil is brought to cracking temperature and pressure. And, it may be noted in this 30 connection that the oil while passing through the heating or fire zone is preferably maintained in the liquid phase.

In the drawings:

Fig. 1 is a vertical sectional view of the 25 furnace construction and apparatus mounted therein.

Fig. 2 is a side elevation of the apparatus.

Fig. 3 is an end elevation.

Before describing the apparatus in detail 40 a general statement of the essential features of the apparatus and process may be given. The fuel oil is fed by means of a charging pump into a continuous coil of say 4-inch pipe suitably separated within a furnace. 45 The arrangement is such that the fuel oil may be heated at a pressure of 50 pounds upwards to a cracking temperature. The fuel oil while still in the liquid phase is transferred to a vapor chamber of sufficient size 50 to readily take care of the precipitated carbon which in the illustration given in the drawings takes the form of a coil of pipe 10 inches in diameter. The vapors pass out of the vapor chamber through suitable risers 55 and are then subjected first to an initial or reflux condensing action and then to a final or complete condensation. The reflux condensation is so controlled as to condense the heavier portions of the vapor which may be 60 subjected to further cracking reactions. In the present instance the reflux condensate is continuously returned to the charging line and mixed with a fresh charging stock. The lighter vapors are condensed by the second 65 or final condensation. The unvaporized por-

tion of the oil which enters the vapor chamber is drawn off, preferably continuously, and in such a manner as to keep the carbon in suspension to the greatest possible extent in the oil which is being so drawn off. In 70 this connection it may be here noted that it is highly desirable to keep the residue from getting too heavy and thus concentrating and precipitating the carbon in the vapor chamber instead of removing it with the drawn 75 off residuum. This is accomplished by regulating the gravity of the residue leaving the vapor chamber.

Describing now more in detail, 1 designates the furnace having Dutch oven 2 and burners 3. In the furnace or firing zone are supported the heating elements which in the present instance take the form of a coil of four inch tubes 4 having return bends 5. The furnace is equipped with the usual stack 6. 7 designates the inlet for the charging oil which is connected to the charging pump 7'. In the present instance the heating element comprises 14 tubes, each of four inches internal diameter and twenty feet in length. The oil passes from the upper bank of the four inch tubes to the lower bank through nipple 8, and connection 9. From the last tube 10, of the heating element, the hot oil under pressure passes by means of a U-bend 11, into a vapor chamber 12. This vapor chamber 12 in the present instance, comprises four tubes each of 10-inch internal diameter and 90 20 feet long, connected to each other by means of yokes. The generated vapors pass out through the risers or standpipes 13 to a common header 14. The risers 13 in the present instance take the form of four inch pipes and T's respectively. To the header 14 are connected two vapor lines which in the present instance are pipes of 10-inch internal diameter and some 20 or more feet long. These vapor lines 15 slope upwardly from the header 14 as shown clearly in the drawings. That portion of the vapors which condenses 100 in the vapor lines 15 and header 14 is returned as reflux condensate by means of the pipe 16, which is of substantially four inch diameter, to the inlet pipe 7, the arrangement 105 being such that the reflux condensate is mixed with the fresh charging oil and is retreated 110 in the heating element referred to.

Carbon or other solid material, such as pipe scale or iron sulphide, mechanically carried over with the vapors may be precipitated 115 into the tube leg 17, which serves as a trap for this purpose. The liquid residue in the vapor chamber is drawn off through a swedge nipple 18, which leads to outlet line 20. A throttle valve 19 is interposed in the line 20 and serves as an emergency valve. In normal operation this valve 19 is open. The pipe 20 is connected to a residuum cooler 42, and at the outlet side of this cooling coil is a throttle valve 43. We also preferably provide an 120 125 130

auxiliary drawoff pipe 21, having valve 21a, which is connected to an auxiliary residue cooler 44, controlled by throttle valve 45. The auxiliary drawoff line and cooler are 5 used in the event that the first drawoff line or cooler becomes clogged or stopped up with carbon.

It is desirable to carefully regulate the temperature of the oil in the heating coil.

10 We may place a pyrometer 22 in the upper bank of the heating coil, and also pyrometers 23, in the U-11, to register the temperature of the liquid as it is being transferred from the heating zone to the vapor chamber. Pyrometers 24 show the temperature of the vapors passing out of the vapor chamber. These pyrometers may be of the recording type desired.

15 It is desirable to prevent any of the reflux 20 condensate from falling back into the vapor chamber. To this end the pipes 13b which lead from the risers to the header 14, slope downwardly toward the header, as shown clearly in Fig. 3. That portion of the vapors 25 which are not condensed by the time they pass through the vapor lines 15 are conveyed through pipe connection 25 to water condenser coil 26, in condenser box 27. The distillate, together with uncondensable gases, 30 passes into the receiver 28 through valve 29. This valve 29 is open in normal operation and acts as an emergency valve. The receiver is provided with liquid drawoff 29', having control valve 30, and is also provided with gas 35 outlet 34, having control valve 35. The pressure is regulated by suitably controlling the valves 30 and 35. A meter 31 is interposed in the drawoff 29'. We also provide a sample drawoff line controlled by valve 32.

40 We have heretofore stated that the reflux condensate passes from the header 14 through pipe 16 to the inlet pipe 7. More specifically this is accomplished as follows: The reflux condensate passes out of the header 14 to pipe 45 36, thence to connection 38, to pipe 39. The reflux condensate from the vapor lines 15 passes through pipes 15', into the connection 38, and thence to the pipe 39 above referred to. The pipe 39 in turn connects to the pipe 16.

50 Carbon and scale traps 37 are also provided as shown more clearly in Fig. 3. An emergency valve 41 is also inserted in the pipe 16. In order to determine the level of the liquid in the vapor chamber, we provide the super- 55 imposed try-cocks 46, which are connected by pipe 47, to cooler 48, having drawoff valve 49. There is a set of these try-cocks and associated condenser at various parts of the system wherever it is desired to take samples of hot 60 oil.

We will now describe the general operation of the process prior to describing the detailed operation of specific runs.

The 4-inch heating coils and 10-inch expansion chamber are charged with the fuel oil

to be treated, by means of a pressure pump such as a triplex Gould pump, until the level of the oil in the 10-inch expansion chamber is one-half of its diameter. The 4-inch tubes are full of oil before the furnace is fired. 70 Before charging the 4-inch tubes and 10-inch expansion chamber with oil to be cracked, the residuum oil drawoff is closed. The uncondensable gas control valve and the pressure distillate receiver control valve are also closed. 75 The entire apparatus is a closed one with all parts of same being in free communication with one another. The 4-inch heating tubes and 10-inch expansion chamber having been charged with 340 gallons of the fuel oil to be treated, the portion of oil in the 4-inch heating tubes, is now subjected to heat by means of the burners set within the Dutch oven of the furnace. After heating the oil in said 80 4-inch tubes for a period of an hour or so, the transfer liquid from the 4-inch heating tubes to the expansion chamber reaches a temperature of approximately 400° F. The triplex raw oil charging pump is then started and the raw oil is circulated through the 4-inch 85 heating tubes into the expansion chamber back to the storage tank, from which it is again drawn by the pump. The furnace fires are increased progressively as the furnace heats up so that the rapidity of heating 90 the full raw oil is increased as shown by the temperature recording instrument set in the transfer liquid line from the 4-inch heating tubes to the 10-inch expansion chamber.

The hydrocarbon vapors within the apparatus exert their vapor pressure upon the liquid of the oil in said apparatus until it reaches the predetermined operating pressure desired, which, in the tests submitted ranged from 105 to 135 pounds per square inch. The 105 operation pressure is reached two to three hours before the normal pressure distillation of cracking takes place. Although the temperature of the transfer liquid has reached the desired temperature of cracking, the expansion chamber which is insulated, the risers from said expansion chamber, the lower manifold and vapor lines leading to the water condenser are not in temperature equilibrium 110 with the temperature of the transfer liquid passing from the 4-inch heating tubes to the expansion chamber so that high Baumé gravity pressure distillate dribbles over for several hours before actual full stream pressure distillation takes place. The full stream 115 pressure distillation does not take place until the entire apparatus is in thermal equilibrium with the different parts of the system.

The pressure distillate oil is collected in a receiver having a control valve, and the pressure distillate leaving the receiver is metered as it passes to a storage tank and there gauged. The raw oil gauged into the apparatus is metered so that a definite amount of said raw oil passes into the appa- 120 125 123

ratus in unit time. The residual oil leaving the expansion chamber passes to a storage tank where it is gauged, as we have found up to the present time that no meter will give 5 the quantity of residual oil correctly, due to the amount of suspended carbon therein resulting from the cracking reaction. The permanent or uncondensable gases resulting from the thermal and pressure treatment of 10 the oil are controlled by means of a valve, so that a constant, fixed pressure may be maintained upon the apparatus and said permanent gases are metered and give an indirect measure of the amount of cracking taking 15 place in unit time. The generated vapors from the expansion chamber passing by means of risers to a header connected with vapor lines condense in part to a liquid and said liquid condensate does not pass back 20 into the expansion chamber but is diverted by means of piping back into the 4-inch heating tubes set within the furnace.

The control factors involved in the thermal and pressure distillation in the apparatus used are (1) pressure, (2) temperature, (3) rate of fuel oil into the system, (4) rate of pressure distillate formation, (5) rate of residual oil formation, (6) permanent or uncondensable gas formation.

30 The control of pressure upon the apparatus is the simplest factor involved in cracking. The pressures of the four tests submitted range from 105 to 135 pounds per square inch.

35 The temperatures of the various parts of the apparatus must be in equilibrium with one another for maximum production of pressure distillate oil in unit time. The temperature of the transfer liquid from the four 40 inch heating tubes to the expansion chamber can be maintained relatively constant and offers no particular difficulty. The temperature of the residual oil leaving the expansion chamber can be maintained at the degrees F. desired as it is clearly a function of 45 the temperature of the transfer liquid. The temperatures of the lower manifold attached to the vapor lines going to the water condenser and the temperature of the vapors 50 passing into the water condenser are more difficult of control due to fluctuating weather conditions affecting markedly the amount of condensate which refluxes back into the heating zone to be subjected to another cycle of 55 operation. However, when weather conditions are static the temperature of the vapors passing into the water condenser can be controlled within a few degrees F.

60 The control of the amount of fuel oil fed into the system per unit time may be maintained at the rate desired, for it is sometimes found necessary to change the rate of fuel oil going into the apparatus as a function of the changing weather conditions during 65 an operating period, for fluctuating

weather conditions, such as wind, and rain, following upon a static condition of the atmosphere increase greatly the amount of reflux condensate which passed back into the heating zone. It is then necessary to cut 70 down the amount of fuel oil pumped into the heating zone during the period when excess reflux condensation takes place. To overcome this excess of reflux condensate the furnace fires can be increased to take care of this 75 relatively cool reflux condensate which is going back into the system. However, by increasing the furnace temperature or the quantity of British thermal units passing into the furnace in a given time, allows the 80 normal amount of pressure distillate to pass over into the receivers. But we have found it more advantageous to cut down the quantity of fuel oil passing into the apparatus in unit time so as to offset inclement weather 85 conditions. By cutting down the amount of fuel oil going into the apparatus during such weather conditions, an excessive furnace temperature is avoided and the consequent excess carbon deposition in the four inch 90 tubes and fire hazards are cut to a minimum.

The rate of pressure distillate formation and the gravity of same is a function of the amount of cracking taking place in unit time. The Baumé gravity of the pressure 95 distillate may be varied at will and dependent upon the market demands of the quality of the gasoline, kerosene, and gas oil resulting from the redistillation of the pressure distillate. The quality of pressure distillate 100 can be controlled between 48 and 52° Baumé, quite readily although it may vary between the wide limits of 42 to 80° Baumé gravity. The amount of pressure distillate taken off per hour may range between 40 105 and 65 percent, although during some operating hours as high as 85 percent of the raw oil going into the system in one hour can be taken off as pressure distillate, but the quality 110 is low.

The rate of flow per hour of residual oil passing out of the expansion chamber is dependent upon how much pressure distillate oil is taken off. It has been found that when a high percentage of pressure distillate oil is taken off that the residual oil becomes very heavy and viscous and precipitates an inordinate amount of carbon and pitch in the expansion chamber. In this particular apparatus this feature is not desirable for it is our desire to flood out the carbon in a colloidal condition in the residual oil and utilize it as such for fuel purposes, for the B. t. u. content per pound of such an oil is high, 115 due to the suspended and colloidal character of the carbon dispersed through the oil. The permanent or uncondensable gases formed during the cracking reaction are indicative of the extent of the cracking of the 120 125 130

fuel oil and is an indirect check as to whether overcracking is taking place in the cracking system.

The carbon formed in the runs on the Wayside, Oklahoma and Augusta-Elbing fields of Kansas fuel oils, was of a highly porous character. The carbon in the expansion chamber, being of a honeycomb structure, bulked large in volume comparative to its weight. The honeycomb structure was interspersed with pitchy material which indicated one of two facts: that at periods during the test too much pressure distillate had been taken overhead and deposited the pitch out of solution in the residuum oil; or that the cracking reaction takes places progressively to pitch hydrocarbons before carbon is actually formed, for upon opening the expansion chamber it was noted that layers of carbon built up from the lower side had slight amounts of pitchy material between the interstices of the honeycomb structure. Many stalactites of pitch and carbon which were brittle, containing oily material were found on the upper portion of the expansion chamber. The stalactites had a relatively high melting point. The carbon was easily removed from the expansion chamber in slabs having the form of the 18-inch expansion tubes, leaving no adhering hard carbon attached to the walls of the expansion chamber. In the tests submitted practically all of the carbon was deposited in the expansion chamber wherein it was readily removed at the end of a run. The carbon formed is a function of the amount of oil cracked and varies within very wide limits, for a gas oil from a mid-continent field or eastern field produced very much less carbon per gallon of raw oil cracked comparative to residual or fuel oils. In the runs submitted the pounds of carbon per gallon of fuel oil treated ranged between 0.21 to 0.29 pounds.

We will now describe the detailed operating condition and results obtained in treating certain specific charging stocks. The charging stock in the first run was Wayside fuel or petroleum tar; in the second run a petroleum tar obtained from the mixture of Augusta and Elbing crudes; the third run from Delaware petroleum tar; and the fourth a mixture of 50 percent of the Augusta-Elbing blend and 50 per cent of Wayside.

The Wayside fuel oil was of 23.6 Baumé gravity represented 72.3 per cent of the crude petroleum oil. The normal gasoline yield of 53—54 Baumé gravity in the Wayside crude petroleum is 17.4 per cent. By cracking this 72.3 per cent of Wayside fuel oil under heat and pressure 13.8 per cent of 58° Baumé gravity gasoline was produced on the basis of the crude petroleum. By cracking the fuel oil fraction of the crude petroleum an additional 75 per cent of gasoline was pro-

duced on the basis of the crude petroleum over that which was present in the crude oil as it came from the well.

The average operating conditions of the run while on pressure distillation were: pressure 105 pounds; furnace temperature 1600 degrees F.; the transfer liquid from the heating tubes to the expansion chamber was 850 degrees F., and the residual oil leaving the expansion chamber 770 degrees F. The aerial temperature average 573° F. The gallons of raw oil fed into the cracking apparatus over a period of 35 hours on pressure distillation was 218.7 gallons per hour, the average gallons of pressure distillate of 48.2 Baumé gravity, per hour was 94.9, while 111.9 gallons of residual oil of 19.6 gravity was produced hourly.

The gasolene production per hour on pressure distillation was 41.8 gallons, while kerosene showed 24.6 gallons and the gas oil also showed 24.6 gallons per hour.

Upon distilling the Wayside fuel oil at atmospheric pressure down to coke the yield was 8.1 per cent on a weight basis of the fuel oil. Upon subjecting this same fuel oil to heat and pressure, 7656 gallons of fuel produced 2100 pounds of dry carbon, which calculates against the oil treated on a weight basis 3.6 per cent. This fuel oil is a heavy carbon forming oil, but in this apparatus the deposition is so controlled that practically all of it deposits in the expansion chamber away from the heating zone where no "hot spot" formation is possible. The carbon in the expansion chamber was of a highly porous character, light, and occupied a relatively large volume of space for its weight comparative to carbon formation when a mid-continent oil is cracked under heat and pressure under similar conditions of treatment.

In the second run the fuel oil resulting from the atmospheric pressure distillation of the Augusta and Elbing (Kans.) field represented 55.2 per cent of the crude petroleum oil. This crude petroleum oil, upon atmospheric distillation in ordinary crude stills, produced 17.1 per cent of 54 Baumé gravity gasolene. By cracking the 55.2 of 24.3 Baumé gravity fuel oil, the yield of gasolene calculated against the crude oil was increased 16.3 per cent, or 100 per cent additional gasolene was produced by cracking, over that which was normally present in the crude oil to start with.

The operating conditions, as an average, were as follows: The pressure was 120, the furnace temperature 1625° F., the transfer liquid from the heating zone to the expansion chamber was 857° F., while the residual oil showed 762° F., and the reflux 647° F., while the manifold liquid showed 790° F., and the aerial temperature 586° F.

The average gallonage of raw oil fed into the system per hour over a period of 25½

hours, on pressure distillation, showed 204 gallons, producing therefrom 119.1 gallons of pressure distillate of 49.2 Baumé gravity and 73.5 gallons of residuum oil of 16.4 Baumé gravity. On pressure distillation, the gasoline produced was 60 gallons per hour, kerosene 16.9 gallons and 40 gallons of gas oil, as an average, per hour.

The Augusta-Elbing-Kansas field fuel oil, upon distillation at atmospheric pressure to dry coke, yielded 6.7 per cent on a weight basis of the oil. Upon cracking, the fuel oil, at an average pressure of 120 pounds and transfer liquid from the heating zone to the insulated expansion chamber of 857 degrees, yielded 2.8 per cent of carbon on a weight basis against the fuel oil cracked. The condition of the carbon in the expansion chamber, where the bulk of it was deposited, was of a honeycomb structure interspersed with pitchy hydrocarbon material, and quite black in color, and with widely different characteristic properties than the grayish carbon formed from the atmospheric distillation to coke. When the carbon resulting from the cracking reaction is treated with carbon bisulphide to extract whatever oil or solid hydrocarbons which may be present, the carbon shows a lamp-black, light product, and of a more or less velvety black color.

The following disclosures cover the details of the third run on a Delaware Oklahoma fuel oil of 21.6 Baumé gravity and represents 41.2 per cent of the Delaware crude petroleum. This Delaware petroleum, upon normal distillation, yielded 18 per cent of gasoline. By cracking the fuel oil, after topping off the gasoline, kerosene and gas oil by ordinary distillation, an additional 13 per cent of gasoline was produced on the basis of the crude oil. By cycling the fuel through the apparatus once, the normal gasoline content of the crude oil was increased 75 per cent over that which was present as it left the well.

The average operating conditions of the run were: pressure, 130 pounds; furnace temperature, 1658° F.; transfer liquid from the heating zone to the expansion chamber, 846° F.; residual temperature, 765° F. and vapor temperature, 557° F., the above values being the averages while on pressure distillation. The fuel oil average per hour was 238.7 gallons during 21 hours of pressure distillation; which yielded, under heat and pressure, 133.3 of a 43.8 gravity pressure distillate and 78 gallons of a residuum oil of 14.0 Baumé gravity.

The gasoline production per hour, while on pressure distillation of 21 hours, was 75.7, with the gallonage of 18.3 for kerosene and 37.9 for gas oil.

When the Delaware fuel oil was distilled to dry coke at atmospheric pressure, the per cent of carbon was 9.4 against the fuel oil, on a weight basis. By subjecting this fuel oil

to pressure distillation, the percentage of carbon, by weight, was 3.6 of the oil treated. The Delaware fuel oil is a higher pitch forming oil than either the Wayside or the Augusta-Elbing fuel oil.

The fourth and last illustrative run was made with a mixture composed of 50% Wayside fuel oil and 50% Augusta, Elbing fuel oil. The mixture having a Baumé gravity of 23.8 was treated under pressure distillation over a period of 15 hours and 15 minutes, treating, as an average of said fuel oil 363.5 gallons per hour during that period of time. The pressure distillate averaged 200 gallons per hour of 46 Baumé gravity and 141.8 gallons of 15.6 gravity residuum oil.

The gasoline production per hour on pressure distillation was 90 gallons, while kerosene was 50.2 gallons and 54.1 gallons of gas oil per hour were recovered.

The operating conditions were: pressure, 135 pounds; furnace temperature, 1637° F.; transfer liquid from the heating zone to the expansion chamber was 829° F., the residuum oil leaving the expansion chamber showed an average of 784° F., while the vapor temperature averaged 593° F.

The per cent of carbon was 7.4 on a weight basis when the fuel oil was distilled to dry coke at atmospheric pressure. Upon pressure distillation of the fuel oil, 2.83 per cent resulted on a weight basis against the oil treated. The carbon in the expansion chamber was of a porous, honeycomb structure interspersed with pitchy hydrocarbon material.

We claim as our invention:

1. A continuous process for cracking hydrocarbons, consisting in conducting a stream of hydrocarbons through a heating zone, where a cracking temperature in excess of 800° F. is maintained, in discharging the highly heated stream of hydrocarbons into a separating chamber and depositing the carbonaceous residue in said chamber, in maintaining the contents of said separating chamber at a temperature lower than that of said heating zone, but sufficiently high to cause free evaporation of the relatively low boiling point liquids introduced thereto, in removing the carbonaceous residue from said separating chamber, in discharging the vapors from said separating chamber and passing the same to a reflux condensing zone, in precipitating solid and coke-like particles entrained with the vapors therefrom, prior to their introduction to the reflux condensing zone, in permitting precipitation of additional coke-like and solid particles from the reflux condensate separated from the vapors in the reflux condensing zone, in returning the reflux condensate, free from such coke-like and solid particles, to said stream of hydrocarbons flowing through the heating zone, and in continuously transmitting the mixed

hydrocarbons through said heating zone and into said separating chamber.

2. A continuous process for cracking hydrocarbons, consisting in conducting a stream of hydrocarbons through a heating zone, where a cracking temperature in excess of 800° F. is maintained, in discharging the highly heated stream of hydrocarbons into a separating chamber and depositing the carbonaceous residue in said chamber, in maintaining the contents of said separating chamber at a temperature lower than that of said heating zone, but sufficiently high to cause free evaporation of the relatively low boiling point liquids introduced thereto, in removing the carbonaceous residue from said separating chamber, in discharging the vapors from said separating chamber and passing the same to a reflux condensing zone, in precipitating solid and coke-like particles entrained with the vapors therefrom, prior to their introduction to the reflux condensing zone, in precipitating additional coke-like and solid particles from the reflux condensate separated from the vapors in the reflux condensing zone, in returning the reflux condensate, free from such coke-like and solid particles, while at a temperature in excess of 550° F., to said stream of hydrocarbons flowing through the heating zone, in continuously transmitting the mixed hydrocarbons through said heating zone and into said separating chamber.

3. A process for cracking hydrocarbons, which consists in conducting a stream of hydrocarbons through a heating zone, where a cracking temperature is maintained, in discharging the resultant highly heated stream of hydrocarbons into a separating chamber and depositing the carbonaceous residue in said chamber, in maintaining the contents of said separating chamber at a temperature lower than that of said heating zone, but sufficiently high to cause free evaporation of relatively low boiling point liquid from the carbonaceous residue, in removing the carbonaceous residue as it accumulates in said chamber and discharging it from the system, in discharging vapors in an upward direction from said separating chamber to a reflux condensing zone, in the precipitating coke-like and solid particles entrained with the vapors passed from the separating chamber to the reflux condensing zone, prior to the admission of the vapors to the reflux condensing zone, in condensing the high boiling point fractions from the vapors in the reflux condensing zone, in returning the reflux condensate, free from solid and coke-like particles entrained with the vapors passing from the separating chamber to the reflux condensing zone, and mixing the same with the charging stock passing through said heating zone, and in continuously transmitting the mix-

ture through said heating zone and into said separating chamber.

4. A continuous process for cracking hydrocarbons, consisting in conducting a stream of hydrocarbons through a heating zone, wherein a cracking temperature is maintained, in discharging the resultant highly heated stream of hydrocarbons into a separating chamber and depositing the carbonaceous residue in said chamber, in maintaining the contents of the separating chamber at a temperature lower than that of the heating zone, but sufficiently high to cause free evaporation of relatively low boiling point liquid constituents therein, in removing the carbonaceous residue from said separating chamber, in discharging the vapors from said separating chamber and in passing the same to a reflux condensing zone, in removing from the path of the vapors liquid condensed from the vapors during their passage from the separating chamber to the reflux condensing zone, together with such solid and coke-like particles as are precipitated from the vapors and preventing such liquid and coke-like particles from entering the reflux condensing zone, in returning reflux condensate separated from the vapors and mixing the same with additional charging stock and continuously transmitting the mixture through said heating zone and into said separating chamber.
